UNITED STATES PATENT OFFICE.

ALBERT I. BENNETT, OF FORT ATKINSON, WISCONSIN.

THERMOSTATIC CIRCUIT-CLOSER.

1,263,190.

Specification of Letters Patent. Patented Apr. 16, 1918.

Application filed April 14, 1917. Serial No. 162,094.

To all whom it may concern:

Be it known that I, ALBERT I. BENNETT, a citizen of the United States, residing at Fort Atkinson, in the county of Jefferson 5 and State of Wisconsin, have invented new and useful Improvements in Thermostatic Circuit-Closers, of which the following is a specification.

My invention relates to electric automatic 10 fire alarms and has for its objects; first, to provide an efficient electric alarm which is controlled by a sensitive thermostatic switch, which when the thermostat reaches a pre-determined degree of heat closes a circuit 15 and thereby actuates the alarm, second, to provide an efficient automatic electric fire alarm system having a number of alarms and a number of switches whereby when any one of the switches is closed all of the 20 alarms in the system are operated; and thirdly, to provide an electric alarm system having a number of switches and a number of alarms and an annunciator whereby, when one of the switches in the system is 25 closed, all the alarms in the system are actuated and the annunciator is actuated to show which switch is closed.

I attain these objects by the mechanism illustrated in the accompanying drawings 30 forming a part of this specification, in which:—

Figure 1 is a top plan view of an alarm device embodying my invention,

Fig. 2 is a side elevation of the same in 35 partial section,

Fig. 3 is a diagram of the wiring system of my invention.

Like characters of reference indicate like 40 parts in the various views.

In the drawings 1 indicates the base of 45 the alarm. Said base is metallic and is a conductor of electricity. Mounted on said base is a signal 2 of the electromagnetic type comprising electromagnetic elements 3, a 50 vibrating arm 4 of metal and positioned to be actuated by said electromagnetic elements 3, a circuit breaker 5 in operable connection with said vibrating arm and adapted to hold the circuit closed when said arm is in its 55 distant position relative to said electromagnetic elements, and to open the circuit when said arm is in its closed position respecting said electromagnetic elements 3, and a spring pivot 6 for holding said vibrating 60 arm away from said electromagnetic ele-

ments, said circuit breaker being in circuit with said electromagnetic elements 3 whereby when said signal is energized the vibrating arm is moved to and fro. An extension arm 7 of said vibrating arm 4 has a knocker 60 8 at its upper end and is positioned relative to a gong 9 fixedly mounted on said base 1 and insulated therefrom so that it strikes the gong as said arm 4 moves to and fro as hereinbefore described. The electromagnetic elements 3 are mounted upon a frame 10. The spring pivot 6 is also mounted on said frame, said vibrating arm 4, spring pivot 6, frame 10, and base 1 being in metallic contact. A stationary contact 11 of 70 the circuit breaker 5 is mounted upon an extension of frame 10 and is insulated therefrom, said contact being in operable relation with extension 12 of vibrating arm 4. An insulated electric conductor 13 leads 75 from stationary contact 11 to one end of the contactor in the electromagnetic elements 3. Thus one conductor of the circuit to the electromagnetic elements 3 is composed of conductor 13, contact 11, extension 12, vibrating arm 4, frame 10, and base 1. A binding post 14 is mounted upon base 1 in metallic connection therewith for convenient connection with an electric circuit. An insulated conductor 15 is in electrical connection with the other end of the conductor of electromagnetic elements 3 and leads down underneath the base 1 through a convenient hole therein. A dust cover 16 is mounted on base 1 in a usual manner and 80 has an opening therein to allow arm 7 to operate therethrough. The above described electric signal is of usual construction and needs no further description for the present purposes, except to say that when it is in 85 circuit with an electric energizer the arm 4 vibrates to and fro thereby causing knocker 8 to strike gong 9.

A thermostat 17 of usual construction having a contact 18 on its upper surface and a 100 stud 19 projecting from its lower surface is mounted upon base 1 by means of stud 19 and a nut 20 screw threaded thereon. Insulating washers 21 prevent said stud and nut from contacting with said base. An 105 electric conductor 22 has one end confined between the lower washer 21 and nut 20 and is in electric connection with said nut, and said conductor 22 is connected with a binding post 23 mounted upon base 1 and in- 110

sulated therefrom whereby said conductor 22 may be conveniently connected to an electric circuit. A support 24 is mounted upon base 1 and insulated therefrom by insulating washers 25, nuts 26 screw threaded on said support confining said base 1 between said washers. A contact bar 27 has one end thereof pivoted at the upper end of support 24. Said contact bar extends over and 10 across thermostat 17 and a contact point 28 is formed thereon and positioned in the path of contact 18 of said thermostat. Said contact bar and thermostat with their appurtenant parts form a thermally operated switch 15 which closes when the thermostat reaches a predetermined degree of heat. A stud 29 is mounted on said base 1 and insulated therefrom by insulating washers 30, nuts 31 screw threaded upon said stud confining 20 said base between said washers. Said stud extends upwardly through a hole 32 of contact bar 27 located near the free end thereof. A supporting nut 33 is screw threaded upon stud 29 and engages the bottom side of said 25 contact bar, thus supporting one end of the same. A spiral compression spring 35 encircles said stud and bears down upon bar 27 and a pair of washers 34 engages with the ends of the spring. A nut 36 screw 30 threaded upon said stud engages the other end of said spring and compresses the same. A pointer 37 of contact bar 27 extends from the free end of the same. A standard 38 is mounted upon said base 1 by means of 35 nuts 39 screw threaded thereon engaging insulating washers 40 and confining said base between them. Said standard 38 has a scale 41 inscribed thereon in proximity to the pointer 37 whereby it is possible to adjust said contact bar 27 by means of supporting nut 33 so that the contact 18 of thermostat 17 will contact the contact point 28 at a certain temperature. By reason of the spring engagement to hold down said 40 contacting bar 27 the thermostat cannot be injured if the temperature were to rise to such a point that contact 18 would move beyond contact point 28. In such an event said contact pushes the contact bar against 45 the spring 35 and raises the same, no injury being done upon the thermostat thereby. The conductor 15 is confined between the lower nut 31 and washer 30 and is in metallic contact with stud 29. An electric conductor 42 has one of its ends confined between lower nut 31 and washer 30 and is in electrical contact with said stud 29. A binding post 43 is mounted upon base 1 and is insulated therefrom. The other end of conductor 42 is in electrical contact with said binding post for convenient connection with an electrical circuit for purposes hereinafter described.

An electric battery 44 is provided and is

of usual construction having a feed wire 65 45 leading from one pole thereof and a return wire 46 leading from the other pole thereof. See Fig. 3.

It will be noted that the terms feed wire and return wire are used merely to signify 70 the different wires and do not designate the direction of the flow of the current therethrough. Said feed wire leads from said battery to an annunciator of usual construction and having an annunciating device for 75 each signal in the system. Each annunciating device consists of an electromagnetic element 48 in operable relation with a pivot arm 49, and having a spring 50 holding said pivot arm normally in a distant position from 80 said electromagnetic element and against a stop 51. The outer end of said pivoted arm 49 is formed to attract attention. Sight openings 52 are placed in the side of the annunciator casing, there being one for each 85 annunciating device. These sight openings are positioned respecting outer ends of said pivoted arms so that said ends are in registry with their corresponding sight openings when the pivoted arms are in close relation 90 with said magnetic elements whereby it can be determined which alarm circuit is closed. Branches 54 of said feed wire lead to one end of the electric conductor of each magnetic element 48 of the annunciator. The 95 wires 53 lead from the other ends of each of said electric conductors of said magnetic elements and are connected to the binding post 23 and are thus in electrical connection with the thermostats 17 as hereinbefore described. Return wires 46 lead from said battery to the binding post 14 of each signal. A wire 55 is connected to the binding post 43 of each signal.

When the system is installed in a building signals are placed at intervals throughout the building. The annunciator is placed at a convenient position therein.

In the operation of the device the circuits are normally opened and no current flows 110 therethrough. However, if the temperature around one of the signals rises so that the thermostat moves contact 18 into contact with contact point 28 the circuit for that signal is closed and current flows therethrough actuating the alarm and the annunciator as hereinbefore described. The closing of said circuit alarm closes a circuit by which each of the other alarms in the system is actuated. This second circuit flows 115 through feed wire 45 through the same contactor as the first mentioned circuit up to the stud 29 where it branches and by means of conductors 42 and binding posts 43 and the wire 55 flows to each of the signals in 120 the system actuating the same and returning over the respective return wires 46. The alarm is given over the whole building and 125

by means of the annunciator it can be determined from a contact point just what switch is closed.

Having thus fully described my invention, I claim:

- 5 1. A device of the class described comprising a base, a thermostat thereon, a pair of studs on said base, a contact bar having one end pivoted to one stud and its other end
10 engaging the second stud, a nut on said second stud for adjusting the position of the bar in relation to the thermostat, a coil spring on said second stud engaging with the bar, and a nut on the stud for adjusting
15 the tension of the spring, said thermostat and contact bar being included in an electrical circuit.
- 20 2. A device of the class described comprising a base, a thermostat located thereon, a pair of studs, a contact bar having one end pivoted to one stud and its other end provided with a hole which engages the second stud, said bar having a downwardly projecting contact point arranged in the path
25 of said thermostat, a nut on the said second stud located below the bar for adjusting the
- 30 position of the same in respect to the thermostat, a coil spring on the second stud engaging with the upper face of the bar, and a nut on the stud for adjusting the tension of said spring, said thermostat and contact bar being included in an electrical circuit.
- 35 3. A device of the class described comprising a casing, a thermostat mounted thereon, a pair of studs on said base, a contact bar pivoted to one of said studs and having a contact point arranged in the path of said thermostat, the other end of said bar being bent downwardly, and having its end extending horizontally and provided with an opening to engage the second stud, a nut on said second stud for adjusting the position of the bar in relation to the thermostat, a coil spring on said stud engaging with the upper face of the bar and a standard adjacent the extreme end of the bar and provided with indicating marks, said thermostat and contact bar being included in an electrical circuit.
- 40 45

In testimony whereof I affix my signature.

ALBERT I. BENNETT.
